(57) **CLAIM**

I claim the ornamental design for a vehicle front fender, as shown and described.

DESCRIPTION

FIG. 1 is perspective view of a vehicle front fender showing the new design;

FIG. 2 is a front view, thereof;

FIG. 3 is a side view, thereof; and,

FIG. 4 is a top plan view, thereof.

The broken lines shown in the drawings illustrate portions of the vehicle front fender that form no part of the claimed design.
